UNIDIRECTIONAL SPEAKER

Wilfried Schneider, 59 Perivale Crescent,
Scarborough, Ontario, Canada

Filed Dec. 23, 1971, Ser. No. 211,850

Term of patent 7 years

Int. Cl. D14—03

U.S. Cl. D26—14

FIG. 1

FIG. 2

FIG. 1 is a perspective view taken from the front and from above of the unidirectional speaker embodying my new design;

FIG. 2 is a perspective view taken from the back and from the bottom of the unidirectional speaker embodying my design.

I claim:

The ornamental design for a unidirectional speaker, as shown and described.
